UNITED STATES PATENT OFFICE

95,308

DESIGN FOR A SHOE

Frank Barber, Long Island City, N. Y.

Application March 1, 1935, Serial No. 55,675

Term of patent 3½ years

To all whom it may concern:

Be it known that I, Frank Barber, a citizen of the United States of America, residing in Long Island City, county of Queens, and State of New York, have invented a new, original, and ornamental Design for a Shoe, of which the following is a specification, reference being had to the accompanying drawing, forming part thereof, wherein,

I claim:

The ornamental design for a shoe, substantially as shown.

FRANK BARBER.
